F. P. MURPHY,

INSOLE.

APPLICATION FILED FEB. 17, 1917.

1,268,065.

Patented May 28, 1918.

Invention:

Francis P. Murphy
By Henry J. Miller, Atty.

UNITED STATES PATENT OFFICE.

FRANCIS P. MURPHY, OF NEWPORT, NEW HAMPSHIRE, ASSIGNOR TO W. H. McELWAIN COMPANY, A CORPORATION OF MASSACHUSETTS.

INSOLE.

1,268,065.

Specification of Letters Patent.

Patented May 28, 1918.

Application filed February 17, 1917. Serial No. 149,348.

To all whom it may concern:

Be it known that I, FRANCIS P. MURPHY, a citizen of the United States, residing at Newport, in Sullivan county, State of New Hampshire, have invented new and useful Improvements in Insoles, of which the following is a specification, reference being had to the accompanying drawings, forming part thereof.

10 This invention has reference to improvements in insoles.

One object of the invention is to provide a novel and economical insole strip constituted by two members differing in characteristics whereby the respective members may operate relatively, said members being attached together in a manner to furnish a reinforce to resist the drawing out or pulling out of the stitches whereby the welt and 20 shoe upper are sewed to the insole strip.

Another object of the invention is to provide an insole strip having an indicator whereby in the operation of sewing the welt and shoe upper to a sole the operator may 25 follow said indicator with his eye and thereby adjust the parts under operation to effect the formation of the attaching stitches approximately at or on a predetermined line of said insole strip.

30 Another object of the invention is to provide an insole strip of textile material with a sustaining member of different material.

Other objects of the invention will appear from the following description.

35 The invention consists in the novel insole strip.

The invention also consists in an insole having the improved insole strip.

The invention also consists in such other 40 novel features of construction and combination of parts as shall hereinafter be more fully described and pointed out in the claims.

Figure 1, represents a side elevation of a 45 piece of the improved insole strip of the preferred construction.

Fig. 2, represents a similar view illustrating a piece of the insole strip showing a modified construction.

50 Fig. 3, represents a plan view of an insole having the improved strip.

Fig. 4, represents an edge view of a portion of the insole shown in Fig. 3.

Fig. 5, represents a sectional view of portions of Fig. 3 taken on line 5—5 Fig. 3.

Fig. 6, represents an enlarged cross sectional view of a fragment of the sole taken on line 6—6 of Fig. 4.

Similar characters of reference designate corresponding parts throughout.

In carrying this invention into practice I take a strip 9 preferably of woven fabric cut on the straight or on the bias and having the edges 10 and 11. The strip member 12 has edges 13 and 14, the edge 13 being located adjacent the edge 11 of strip 9 and is attached to said strip 9 by a line of stitches 15, extending parallel to the edges 11 and 13 of said respective strips 9 and 12. These sewing stitches 15, 15 are preferably 70 made with thread contrasting in color with said strips 9 and 12 or with one of said strips. When the strips are sewed together on a sewing machine the outer surface of the strip 12 sustains the upper surface when 75 the strip is fed through the sewing machine whereby the under side of the strip 9 is provided with looped or engaged portions of the stitching thread, as is shown in Fig. 5. The purpose of the strip 9 is to afford 80 strength to form a union between the insole and the upper and welt of a shoe. The purpose of the strip 12 is to afford or facilitate the upstanding of the strip 9 after its attachment to the insole whereby both of said 85 strips 9 and 12 may receive the stitches used to attach the welt and upper thereto. For the purpose of sustaining said strip 9 I may prefer to make the strip 12 of paper and to slightly corrugate the same transversely as is indicated at 12'.

In some cases I prefer to manufacture the insole strip as shown in Fig. 2 in which the strip 16 is made of woven material cut on the bias or having its threads extending diagonally. These strips being attached together by sewing stitches 15 placed similarly to those shown in Fig. 1 and having the same purpose. In the construction shown in Fig. 2 it is found that the bias 95 strip 16 adjusts itself more readily to the curves followed by the insole strip in its attachment to the insole or to the curves followed by the strip in the attachment of the upper and welt to the insole.

After the manufacture of the improved insole strips shown in Figs. 1 and 2 I place the same flatwise with the surface of the strip 12 against an insole A and operate upon the same with a sewing machine and 110

sew lines of stitches *b*, *b* through the strips 9 and 12 and also through the insole A whereby the strip 12 is firmly secured in intimate contact with the surface of the insole and in this sewing operation I follow the edge of the sole A until a suitable length of the insole strip has been attached thereto.

In some cases it is desirable to manufacture the insole A of leather board or other 10 comparatively stiff material and it is to be noted that after the sewing of the insole strip to the insole, the insole A may be shaped to conform to the surface of a last which is made possible by the flexibility of 15 the insole strip.

After the attachment of the insole strip to the sole A, that portion of the insole strip outside of the line of stitches *b*, *b* is turned upward by means of any ordinary 20 lip turning machine or hand implement as may be most desirable, whereby the sustaining strip 12 is located exteriorly of the strip 9.

The insole strip as a whole is at some time 25 treated with shellac or any other suitable stiffening material and the surplus of said shellac or material is drained from the same.

In the sewing operation the insole A is placed on a last with the insole strip uppermost. The edge of the shoe upper is now 30 turned slightly over the last and up and against the raised lip constituted by the raised portion of the insole strip. The welt is now laid against the edge of the upper 35 and progressively follows its curvatures during the operation of the sewing machine which sews stitches through said welt and upper and through the upstanding portion of the insole strip. These sewing stitches 40 draw tightly against the inner surface of the insole strip formed by the strip or member 9 and in the sewing operation the operator follows with his eye the line of stitches 15, which are noticeable by their contrast- 45 ing color, whereby he can gage the line of attaching stitches made by the sewing machine so that this line of attaching stitches, securing the welt, upper and insole strip, may follow a line transversely parallel with 50 and below the line of stitches 15. The line of stitches 15 thus constitutes a guide which assists in preventing the sewing of the attaching stitches beyond the upper edge of

the insole strip or assists in preventing the approach of said attaching stitches so closely 55 to the upper edge of the insole strip as to permit of their being drawn outward through the raw edge of the insole strip.

After the sewing of the welt and upper to this improved insole strip the edges of 60 the upper beyond the line of attaching stitches and the edge of the improved insole lip may be trimmed nearly to the line of stitches 15, whereby the depth of the cavity within said strip may be reduced, thus 65 reducing the amount of filling material necessary to fill said cavity.

Having thus described my invention I claim as new and desire to secure by Letters Patent.

1. An insole having a strip comprising a pair of strip members free at one edge and secured together on a line spaced from the other edge, said members being respectively of woven material and paper. 75

2. An insole having a strip comprising a pair of strip members free at one edge and secured together on a line spaced from the other edge, one of said members having transversely extending stiffening elements. 80

3. An insole having a strip comprising a pair of strip members free at one edge and secured together on a line spaced from the other edge, one of said members having transversely extending corrugations. 85

4. An insole having a strip comprising a pair of strip members free at one edge and secured together on a line spaced from the other edge, one of said members being of corrugated paper. 90

5. An insole having a strip comprising a pair of strip members free at one edge and secured together on a line spaced from the other edge, one of said members being of woven fabric having a raw edge and the other said member being of paper, said securing means being sewing stitches looped over some of the threads of said fabric and drawing said threads closely against said paper. 95

FRANCIS P. MURPHY.

Witnesses to the signature of Francis P. Murphy to the above specification and claims:
